United States Patent Office

Des. 176,536
Patented Jan. 3, 1956

176,536

FLOWER PLANTER

Arthur F. Klingberg, Chicago, Ill., assignor to Bernard Edward Co., Chicago, Ill., a corporation of Illinois

Application January 24, 1955, Serial No. 34,135

Term of patent 3½ years

(Cl. D35—3)

Fig. 1 is a front perspective view of the flower planter showing my new design.

Fig. 2 is a top plan view thereof.

I claim:

The ornamental design for a flower planter, substantially as shown.
